UNITED STATES PATENT OFFICE.

LYMAN M. COOPER, OF DETROIT, MICHIGAN, ASSIGNOR TO ALICE M. COOPER, OF DETROIT, MICHIGAN.

STEAM-TRAP.

992,545.

Specification of Letters Patent.

Patented May 16, 1911.

Application filed October 17, 1910. Serial No. 587,587.

To all whom it may concern:

Be it known that I, LYMAN M. COOPER, a citizen of the United States of America, residing at Detroit, in the county of Wayne 5 and State of Michigan, have invented certain new and useful Improvements in Steam-Traps, of which the following is a specification, reference being had therein to the accompanying drawings.

10 This invention relates to a steam trap designed to remove water of condensation from radiators, steam coils or pipes of a steam heating system in which a low pressure or partial vacuum is maintained in the return 15 end in which a float is used to automatically control the discharge of the water without any waste of steam.

One of the objects of the invention is to provide simple means whereby a person in 20 charge of the system to which the valve is attached can readily clean out the valve without dismounting it and whereby other unauthorized persons cannot tamper with it or disturb it in any manner.

25 The invention consists in the matters hereinafter set forth, and more particularly pointed out in the appended claims.

In the drawings, Figure 1 is a view in 30 longitudinal section through the trap that embodies features of the invention; Fig. 2 is a view in cross section on or about line $x-x$ of Fig. 1.

As herein illustrated a casing 1 is normally closed at its lower end and provided 35 with an outlet nipple 2 and a lateral inlet nipple 3 above its lower end. A cover 4 is detachably secured on the upper end of the casing. A cylindrical plug 5 is secured in the upper end of the opening through the 40 nipple 2. The upper end of the plug is cylindrically counterbored and is provided with a plurality of ports 6. A float 7 has a recessed lower end from which an axial stem 8 depends to form a closure or slide valve 45 normally sealing the port of the plugs 5 when the float is at its lowest position. A stem 9 upwardly extending from the float 7 is reciprocable in an apertured boss 10 formed on the cover 4 and is provided with 50 a central longitudinal slot above the float.

Journalized in a lug 11 on the casing adjacent the slotted portion of the stem 9 is a rock shaft 12 the outer portion of which passes through the gland 13 of a stuffing box which seals the opening through the lug. The 55 outer end of the gland 13 is recessed and the outer end of the rock shaft which lies entirely within the counterbored recess is square, polygonal or otherwise fitted for engagement by a socket-key. A rock arm 14 60 is rigidly secured to the inner end of the rock shaft 12 and passes through the longitudinal slot of the stem 9. By insertion of the proper key into the gland, the rock shaft may be rotated and caused to raise the float. 65 A pin 15 adapted to be engaged by the rock-arms, is secured in the stem transversely across the upper end of the stem slot. To aid in excluding dirt from the valve proper a cage 16 of wire gauze or like foraminous 70 material encircles the nipple 5. By this method of construction the steam trap can be readily emptied by manipulation of the float by the person in charge of the same without dismounting the valve; while at the 75 same time parties not authorized to do so cannot work the valve.

Obviously, changes in the details of construction may be made without departing from the spirit of the invention and I do 80 not care to limit myself to any particular form or arrangement of parts.

I claim as my invention;

1. In a steam trap, the combination with a casing having in its exterior surface a recess, 85 and also having inlet and outlet openings, and a float actuated valve movable within the casing and for normally closing said outlet opening, of a device for raising said valve independently of its operation by the 90 float and projecting through said casing, the outer end of said device being shaped to fit a key and terminating within said recess, whereby the operation of said device by means other than the proper key will be 95 prevented.

2. In a steam trap, the combination with a casing having in its exterior surface a recess, and also having inlet and outlet openings, a float-actuated valve movable within 100

the casing and for normally closing said outlet opening, and a rod connected with said valve and guided in said casing, a rock arm in engagement with said rod, and a 5 rock shaft projecting through said casing, the outer end of said rock-shaft being shaped to fit a key and terminating within said recess, whereby the operation of said device

by means other than the proper key will be prevented.

10

In testimony whereof I affix my signature in presence of two witnesses.

LYMAN M. COOPER.
